THORVALD BERG, OF PORT ANGELES, WASHINGTON

LOG-SPLITTING GUN

Application filed August 30, 1927. Serial No. 216,446.

My invention aims to provide an improved gun for splitting logs by means of explosives, particularly adapted for splitting pulp wood.

- 5 Among the objects of this invention are the provision of means whereby the barrel of the gun, when driven into a log, will automatically engage the fibers of the wood in a manner to resist being blown out by the recoil, there-
 10 by accomplishing more effective splitting than is possible by means of a smooth-barreled gun using an equal charge of explosive, or accomplishing equal results with a smaller charge.
 15 Further objects are to permit the gun to be repeatedly hammered into logs without deformation, to provide a member to receive the driving blows which will not need frequent renewal, to prevent the entrance of
 20 water and dirt into the vent, and to allow ready cleaning or renewal of the vent.

Additional objects and advantages will be apparent to those skilled in the art from the following description and accompanying drawings, wherein a preferred embodiment of my improved gun is illustrated, it being understood that the characteristic features and principles of my invention may be applied in forms other than those herein shown and described.

My present invention contains certain features in common with my copending application Serial No. 181,207, filed April 5, 1927.

In the accompanying drawings,
 35 Fig. 1 is a longitudinal cross section of my improved gun, certain features being shown in side elevation;

Fig. 2 is a top view; and

40 Figs. 3 and 4 are partial side views of the barrel showing alternative forms of the wood-engaging elements or surface configuration.

My splitting gun consists of a barrel comprising, successively, a tapered muzzle 1, a cylindrical chase 2, a taper 3 to the breech portion, and a cylindrical breech portion 4. The tapered muzzle increases rearwardly from a diameter slightly larger than that of the bore to the diameter of the cylindrical chase 2, and the second conical portion or breech taper
 45 3 is near the rear end of the chase, whereby

the barrel is enlarged to the diameter of the breech portion 4.

In the present form of my gun I provide means, preferably in the form of a buttress screw thread 5, Figs. 1 and 2, upon the exterior surface of the chase 2, for engaging the fibers of the wood so as to resist the recoil and utilize the force of the explosion in splitting the log rather than in projecting the gun backwards. I prefer a buttress screw thread for this purpose, as being readily cut on the surface of the barrel by ordinary tools, as allowing easy driving entrance of the gun by reason of the inclined forward faces of the threads, and as strongly holding the gun in place by engagement of the wood fibers against the vertical rear faces of the threads. It is contemplated that the gun will be driven into the log by means of a sledge hammer or the like and not screwed in. Consequently I may finish the surface of the chase with parallel circumferential grooves 6 of shape similar to a buttress thread, (see Fig. 3). I may employ any other finish of similar characteristics, such as a plurality of rasp-like teeth 7, as illustrated in Fig. 4, or other engaging elements wherein the front sides are inclined to permit of easy driving and the rear sides slope abruptly to prevent withdrawal of the log.

The bore 8 of the gun extends back from the muzzle through the greater part of the length of the barrel, this type of gun being a muzzle-loader. Near the inner end of the bore a radial internally-threaded vent hole 9 communicates with the outside of the barrel. The breech of the gun is bored from the rear towards the muzzle with a shallow recess 10 of relatively large diameter, a sufficient thickness of steel for safety being left, as at 11, between the inner end of the bore and the bottom of the recess.

A driving head 12 of tool steel, hard wood, or other suitable material, about twice the length of the recess 10, fits therein, the rearwardly projecting portion preferably being slightly tapered. A block or cushion 13 of fibrous material is placed in the bottom of the recess 10 to absorb the driving shock without injury to the breech of the gun. A

retaining member, such as a cap screw 14, passes through a longitudinally elongated slot 15 in the side of the recess 10 into the driving head, to hold the latter from falling out. The longitudinal elongation of the slot permits the necessary play of the cap screw during the driving.

A removable vent bushing 16, preferably of case-hardened steel, externally threaded, 10 and centrally pierced with a vent hole 17 enlarged at the outer end to receive the end of a fuse, is screwed into the vent hole. This bushing has an enlarged head 18 adapted to project above the outer surface of the barrel, 15 and the breech portion 4 is flattened immediately behind the breech taper 3 to provide a seat 19 for the head 18.

In operation, the gun is loaded from the muzzle with a powder charge and a wad, and 20 is then driven into the log by a sledge hammer, after the manner of a wedge, with the vent preferably upward. The tapered muzzle 1 facilitates driving the barrel into a log, especially of soft wood, without first boring 25 a hole. The inclined faces of the buttress threads force the fibers apart during insertion of the barrel, after which the vertical rear faces engage the fibers, opposing rearward motion, thus holding the gun firmly in 30 the log. The breech taper 3 and the protruding head 18 of the vent bushing 16 prevent water from the log, which may run along the chase 2, from entering the vent and wetting the powder charge. When the charge is 35 fired by a fuse inserted in the hole 17 the log is split by the force of the explosion, and the gun is freed therefrom.

This gun is simple and strong, easily driven 40 into a log, particularly of the varieties of wood used for pulp manufacture, and exceedingly tenacious in its hold when driven home, thus forcing the main energy of the explosion forward into the log. There is nothing about 45 the gun which is weak or readily deranged, and the only parts likely to be injured either by hard usage or corrosion, namely the driving head and the vent plug, are easily, quickly and cheaply replaceable.

It will be understood that I do not limit 50 myself to the exact form of the foregoing disclosure.

What I claim is:

1. In a gun adapted to be hammered into wet logs, in combination, a tapered muzzle 55 portion adapted, when driven in, to wedge apart the fibers of a log, a cylindrical chase adapted to enter a log without further wedging, rearwardly-inclined fiber-engaging elements on said chase, an enlarged breech, a charge-receiving bore within said gun, a vent hole from said bore to the surface of said breech, said breech enlargement being adapted to turn water flowing on the surface of 60 said gun from said vent hole, a removable driving head projecting from said breech,

and a thrust-transmitting cushion between said driving head and said breech, said driving head and cushion being adapted to transmit the shock of hammer blows to said breech and protect said breech from being deformed 70 thereby.

2. In a gun adapted to be hammered into wet logs, in combination, a tapered muzzle portion adapted, when driven in, to wedge apart the fibers of a log, a cylindrical chase 75 adapted to enter a log without further wedging, an enlarged breech, a charge-receiving bore within said gun, a vent hole from said bore to the surface of said breech, said breech enlargement being adapted to turn water 80 flowing on the surface of said gun from said vent hole, a removable driving head projecting from said breech, and a thrust-transmitting cushion between said driving head and said breech, said driving head and cushion being adapted to transmit the shock of hammer 85 blows to said breech and protect said breech from being deformed thereby.

In testimony whereof, I have signed my name to this specification. 90
